SPOON OR SIMILAR ARTICLE

Richard Carlton Gavette, Bristol, Conn., assignor to R. Wallace & Sons Manufacturing Company, Wallingford, Conn., a corporation of Connecticut

Application March 23, 1953, Serial No. 24,157

Term of patent 14 years

(Cl. D54—12)

To all whom it may concern:

Be it known that I, Richard Carlton Gavette, a citizen of the United States of America, residing at Bristol, county of Hartford, and State of Connecticut, have invented a new, original, and ornamental Design for a Spoon or Similar Article, of which the following is a specification, reference being had to the accompanying drawing, forming part thereof.

In the drawing:

Fig. 1 is a front elevational view of a spoon showing my new design;

Fig. 2 is a side elevational view thereof;

Fig. 3 is a rear elevational view thereof;

Fig. 4 is a cross-sectional view of the handle taken at line 4—4 of Fig. 3; and

Fig. 5 is a cross-sectional view of the handle taken at line 5—5 of Fig. 3.

I claim:

The ornamental design for a spoon or similar article, substantially as shown.

RICHARD CARLTON GAVETTE.
